United States Patent Office.

JOHN Q. BIRKEY, OF PHILADELPHIA, PENNSYLVANIA.

Letters Patent No. 75,516, dated March 17, 1868.

IMPROVEMENT IN GAS AND OTHER HEATERS.

The Schedule referred to in these Letters Patent and making part of the same.

TO ALL WHOM IT MAY CONCERN:

Be it known that I, JOHN Q. BIRKEY, of Philadelphia, in the county of Philadelphia, and State of Pennsylvania, have invented certain new and useful Improvements in an Apparatus for Collecting, Neutralizing, or Destroying all Noxious Vapors arising from the Combustion of all Fuel used in Generating Heat; and I do hereby declare that the following is a full, clear, and exact description thereof, reference being had to the accompanying drawings, and to the letters of reference marked thereon, which form a part of this specification, in which—

Figure 1 represents a vertical section of my apparatus.

In the combustion of all fuel used for generating heat there always arises a deleterious odor, which, if not carried off by some mechanical apparatus, causes disease, and, in many instances, death; hence, are found in all apparatus used for the purpose of generating heat, pipes, chimneys, or some contrivance for that special purpose. Now, more particularly in the combustion of gas, and the same of coal or any kind of fuel, we have, arising from the combustion, carbonic acid, along with sulphurous acid, carbonic oxide, and other gases, all deleterious to health.

To construct an apparatus whereby I can have command of all the heat generated, and at the same time collect, neutralize or destroy all the deleterious gases, without the aid of any outlet, whereby more or less of the heat generated escapes with the noxious gases, is my object.

The nature of this invention consists in the employment of a funnel-shaped device, or its equivalent, for collecting the noxious vapors, deleterious gases, and other impurities arising from the combustion of fuel, in combination with a pipe, tube, or outlet, for conducting the said gases and impurities to the vessel where the same are neutralized, substantially as will be hereinafter set forth, and in conducting to and condensing in water or chemical agent the gases, vapors, or other impurities arising from combustion, for the purpose of neutralizing or destroying the evil effects of said gases, &c.

To enable others skilled in the art to make and use my invention, I will now describe its construction and operation.

A represents a drum, with two series of perforations near its base, the lower series being designed to admit the air for supporting combustion, and the upper series to admit air for the purpose of being heated. In addition to these perforations there is a third series near the top of the drum A, for the emission of the heated air. c designates a platform near the base of the drum A, the design of which is to support the vessel B, the said vessel being intended to be filled with water or other chemical agent. D represents a receiver, with a flange at the lower end, which fits tightly in the base of the drum. The receiver D is made conical in form, as seen in fig. 2, and terminates in tube e, the said tube being made to pass through and extend a little above the adjustable top g. On tube e is fitted the goose-neck pipe k, which is intended to pass downwards outside of the drum A, and to have its end immersed in the contents of the vessel B. On a large scale, this pipe may be concealed in the inside of the drum.

I am not held exclusively to the peculiar form or shape, as herein described or manifested, as I have found in my experiments that any shape or form will answer the purpose designed. I have adopted as simple a construction as possible, to demonstrate that combustion can be kept up, and all heat generated to be at our command, without the deleterious gases.

The operation of my invention is as follows: When gas is used, the drum is placed over the flame, so that the receiver will collect and conduct, by means of the pipe k, the deleterious gases, &c., to the vessel containing clear water, or any chemical agent. There they are condensed and completely neutralized, and may be analyzed by one wishing to do so, or the drum may be set over a stove or any other device in which fuel of any kind is consumed, when a like result will follow.

What I desire to secure by Letters Patent, is—

1. The receiver D, for collecting the noxious vapors, deleterious gases, and other impurities arising from the combustion of fuel, in combination with a pipe, tube, or outlet, for conducting the said gases and impurities to the vessel where the same are neutralized, substantially as set forth.

2. I claim neutralizing or destroying the impurities arising from combustion in water or chemical agent, substantially as described.

In testimony that I claim the foregoing as my own, I affix my signature in presence of two witnesses.

JOHN Q. BIRKEY.
